CARBURETOR

Oren F. Teed, Los Angeles, Calif.

Application September 5, 1933, Serial No. 688,154

9 Claims. (Cl. 261—50)

This invention relates to a carburetor for internal combustion engines, and it is a general object of the invention to provide a simple, practical and inexpensive carburetor that is operable to effectively handle comparatively heavy fuels and produce therefrom explosive mixtures for the successful and efficient operation of the engine with which it is used.

An object of the present invention is to provide a carburetor that is operable to readily form explosive mixtures from kerosene, distillates, and other inexpensive fuels to provide for the practical and efficient operation of the engine with which it is connected.

It is another object of the invention to provide a carburetor of the character mentioned that is adapted for use on various types and classes of internal combustion engines.

It is another object of the invention to provide a carburetor of the character mentioned that may be easily and quickly installed on an engine without requiring the use or installation of special devices or appliances.

Another object of the invention is to provide a carburetor of the character mentioned that heats the liquid fuel before it is vaporized and mixed with the air.

Another object of the invention is to provide a carburetor that is smooth and even in operation and that is extremely flexible having a wide range of adjustability or variation.

Another object of the invention is to provide a carburetor that includes the combination of a novel and improved liquid fuel jetting or spraying device and a rotary throttle valve.

It is another object of the invention to provide a carburetor of the character mentioned that is operable to automatically and accurately and properly proportion the mixture of the liquid fuel and air at all speeds of the engine.

A further object of the invention is to provide a carburetor that is simple and sturdy in construction and that is inexpensive to manufacture.

Other objects and features of the invention will be best and fully understood from the following detailed description of a typical form and application of the invention, throughout which detailed description reference is had to the accompanying drawing, in which:

Fig. 1 is a vertical detailed sectional view of the carburetor provided by the present invention. Fig. 2 is an enlarged fragmentary horizontal sectional view taken substantially as indicated by line 2—2 on Fig. 3. Fig. 3 is a vertical detailed sectional view taken as indicated by line 3—3 on

Fig. 1. Fig. 4 is an enlarged fragmentary vertical sectional view of a portion of the valve and of the fuel spraying means, and Fig. 5 is an enlarged horizontal detailed sectional view taken as indicated by line 5—5 on Fig. 1.

The carburetor provided by the invention includes, generally, a body 10 having an air inlet passage 11, a mixing chamber 12, and a heating manifold 13 surrounding the mixing chamber 12, a fuel reservoir 14 in connection with the body 10, means 15 for jetting or spraying liquid fuel into the mixing chamber 12, and valve means 16 for controlling the admission of air and liquid fuel into the mixing chamber 12, and the discharge of the mixture from the mixing chamber 12.

The body 10 may include an integral casting comprising a carburetor bowl 17 and a fuel reservoir 14. The carburetor bowl 17 is substantially round in horizontal cross section and its lower end portion is spherically rounded as illustrated throughout the drawing. A tubular boss 18 projects from the lower end portion of the carburetor bowl 17 and its opening 19 forms the outer end part of the air inlet passage 11. The flow of air into the passage 11 may be controlled by a suitable butterfly valve 20 arranged in the opening 19. The mixing chamber 12 is in the upper portion of the carburetor bowl 17 and is divided or separated from the inlet passage 11 by a transverse wall or partition 21. Two diametrically opposite ports 22 are provided in the partition 21 to pass the air upwardly into the mixing chamber 12 from the passage 11. In the preferred construction, the ports 22 are arcuate or sector-shaped in plan elevation. The passage of air through the ports 22 is controlled by the valve means 16 as will be subsequently described.

The outer walls 23 of the mixing chamber 12 are cylindrically curved about the central vertical axis of the bowl 17. A cap 24 is provided on the outer end of the carburetor bowl 17 and forms the upper end wall of the mixing chamber 12. The cap 24 may be connected with the inlet manifold 25 of the engine. In the particular case illustrated in the drawing, an outwardly projecting flange 26 is provided on the end of the manifold 25 and is connected to the cap 24 by screws or studs 27. A central opening 28 is provided in the cap 24 to pass the explosive mixture of air and the vaporized liquid fuel from the mixing chamber 12 into the manifold 25. The carburetor is adapted to be mounted on either side of the engine as the cap 24 may be detached from the body 10 and the body turned 180°.

The heating manifold 13 is adapted to carry or circulate exhaust gases from the engine for heating the liquid fuel and for heating the walls of the mixing chamber 12. The manifold 13 provides a space in the wall structure of the carburetor bowl 17 that surrounds the mixing chamber 12. The lower end portion of the manifold opening follows the general contour of the lower portion of the bowl 17. A tubular boss 29 projects from the upper portion of the bowl 17 and is adapted to receive the end of a pipe or conduit 30 for supplying the exhaust gases from the engine to the manifold 13. An exhaust opening or outlet opening 31 is provided in the lower outer wall of the carburetor bowl 17 to discharge the gases from the manifold 13. In accordance with the invention, the body or bowl 17 has a central internal structure having a vertical recess or opening 32 forming a continuation of the manifold 13. It will be apparent how the exhaust gases from the engine continuously circulate around in and downwardly through the manifold 13 to discharge from the opening 31. Openings 33 are provided in the walls of the bowl 17 and are normally closed by plates 34. The manifold 13 and other internal portions of the carburetor may be made accessible by removing the plates 34.

The fuel reservoir 14 is an integral part of the body 10 being joined with the bowl 17 by webs 35. The reservoir 14 has a comparatively large opening or chamber 36 whose upper end is closed by a head 37. The chamber is provided to hold the liquid fuel and is supplied with the liquid fuel by a fuel pipe or conduit 38. The admission of the liquid fuel is governed by a float controlled valve 39. The valve 39 is in the nature of a needle valve and is adapted to cooperate with a seat member 40 provided in an opening 41 in the lower end of the reservoir 14. A buoyant member or float 42 is provided in the chamber 36 and has a central opening passing the valve 39. Weighted levers or links 43 operatively connect the float 42 with the valve 39. A fitting 44 is provided on the lower end of the reservoir 14 and has a comparatively small chamber 45 receiving the liquid fuel from the conduit 38. A tubular projection 46 extends through the chamber 45 and carries screening 48 for straining the fuel entering the reservoir chamber 36. The screening 48 is removable being retained in position by a plug 47. The plug 47 also retains the fitting 44 on the lower end of the reservoir 14.

The means 15 for admitting or spraying liquid fuel into the mixing chamber 12 is operable to jet or spray heated liquid fuel into the lower portion of the chamber 12. The means 15 includes a depression or recess 50 in the central internal structure of the bowl 17 extending upwardly to the upper surface of the partition 21. A port 49 extends downwardly and outwardly from the recess 50 to the lower end of the reservoir chamber 36. A central tubular projection 51 extends upwardly from the bottom of the recess 50 and projects above the upper surface of the partition 21. A ring 52 surrounds the projection 51 and has a continuous or annular flange 53 seating on the upper surface of the partition 21. The ring 52 is stationarily clamped in position by a nut 54 threaded on the projection 51.

In accordance with the invention, sets or series of capillary tubes 55 are provided on the ring 52. In the particular form of the inven-

tion illustrated in the drawing, there are two diametrically opposite sets of tubes 55, each set or series being composed of three tubes. The tubes 55 project downwardly from the lower end of the ring 52 to extend into the recess 50. The upper end portions of the tubes 55 are carried in openings or ports 56 in the ring 52. The float 42 controls the valve 39 to maintain the level of the fuel in the recess 50 a considerable distance above the lower ends of the tubes 55 so that the lower end portions of the tubes are submerged in the liquid at all times. The upper end portions of the ports 56 extend laterally or horizontally outward to the periphery of the flange 53. The ring 52 is held stationary by the nut 54 and its two sets of ports 56 are substantially directly above the apertures 22 of the partition 21. The flow or discharge from the ports 56 is controlled by the valve means 16 as will be presently described. It is to be noted that the discharge ends of the ports 56 are horizontal so that the liquid fuel is sprayed horizontally outward into the mixing chamber 12.

The valve means 16 is operable to simultaneously control the flow of air through the partition apertures 22, the discharge of liquid fuel from the ports 56, and discharge of the mixture of air and fuel vapors from the mixing chamber 12 into the manifold 25. The valve means 16 includes a rotatable stem 58 extending upwardly through an opening 59 in the lower end of the carburetor bowl 17 and projecting through the manifold extension 32 and tubular projection 51. A collar 60 is keyed or pinned on the projecting lower end of the stem 58 and has a lug 61 adapted to cooperate with a stop 62 on the bowl to limit turning of the stem. A suitable operating lever 63 is provided on the projecting lower end part of the stem 58.

It is an important feature of the present invention that the carburetor comprises only a single valve for controlling the flow of the incoming air, the discharge of the liquid fuel into the mixing chamber 12, and the final discharge of the fuel vapors and air into the manifold 25. The valve 64 is pinned or keyed to the projecting upper end of the stem portion 58 and is provided in its lower side with a central recess 65, receiving the nut 54 and the flange 53. The valve 64 has two diametrically opposite sector shaped flanges or wings 66 having sliding engagement with the upper side of the partition 21. The wings 66 extend inwardly to the recesses 65 and their inner ends are curved about the axis of rotation of the valve to have sliding engagement with the periphery of the flange 53. In this manner, the wings 66 are operable to control the flow from the ports 56. The outer ends of the wings 66 may be curved about the axis of rotation of the valve and may slidably engage the wall 23 of the mixing chamber as illustrated throughout the drawing. The wings 66 are sufficiently wide to completely or substantially close the apertures 22. As the sets of ports 56 are located above the apertures 22, the wings 66 are operable to simultaneously control the flow through the apertures 22 and ports 56. When the valve 64 is turned toward the closed position, the wings 66 are adapted to successively close the ports 56 and at the same time reduce the flow of air through the apertures 22. In a like manner turning of the valve 64 toward the full open position successively uncovers the ports 56 and allows the passage of more air into the mixing chamber 12. In this manner, the valve 64

is operable to successively control the flow through the ports 56 and vary the flow of air through the apertures 22 to maintain a distinct or predetermined relationship between the discharge of liquid fuel and air into the mixing chamber 12. The ports 56 and the apertures 22 are related so as to insure a proper quantity of liquid fuel in the mixing chamber 12 for each given volume or quantity of air admitted by the apertures 22.

The valve 64 is operable to control the discharge through the opening 22 into the manifold 25. A tubular portion 68 projects upwardly from the body of the valve 64 and its upper end engages the lower side of the cap 24. The tubular part of the valve 64 is provided with diametrically opposite apertures 69. A relatively stationary tube 70 has its upper end carried in the opening 28 and projects downwardly through the tubular portion 68 of the valve. Two diametrically opposite openings or apertures 71 are provided in the walls of the stationary tube 70. In accordance with the preferred form of the invention, the apertures 71 are located substantially 90° from the apertures 22 and sets of ports 56. The tubular portion 68 of the valve 64 is rotatable on the stationary tube 70. The opening and closing of the apertures 71 is simultaneous with the opening and closing of the apertures 22 and fluid fuel ports 56.

Air inlet ports 95 are provided in the partition 21 at points between the ports 22. There may be two sets of ports 95 which are adapted to pass air into the mixing chamber during idling of the engine. A screw 96 is threaded through an opening in the body 10 to regulate one set of ports 95. The inner surfaces of the valve wings 66 and the periphery of the flange 53 are related or grooved so that there is sufficient leakage of fuel from the ports 56 to the ports 22, when the valve is in the closed position, to provide for idling of the engine. In order to facilitate the "running" adjustment of regulation of the carburetor, a by-pass port 80 is provided 45 in the cap 24 and stationary tube 70 between the mixing chamber 12 and the discharge opening 28, which port is controllable by an adjusting screw 81.

In operation, the exhaust gases from the engine are continuously circulated through the manifold 13 to heat the walls of the mixing chamber 12, and the liquid fuel flowing through the port 41. The float 42 controls the valve 39 so as to maintain a sufficient supply of liquid fuel in the recess 50. The incoming air at normal temperatures is admitted through the passage 11 and flows through the apertures 22 into the mixing chamber 12. The liquid fuel is discharged or sprayed outwardly from the ports 56 toward the outer walls 23 of the mixing chamber 12 directly above the apertures 22 so that the incoming air comes into direct contact with the liquid fuel. The hot gases of combustion in the manifold 13 maintain the walls of the mixing chamber 12 in a heated condition so that the contents of the chamber are heated, and so that the discharged liquid fuel from the ports 56 that contacts the walls 23 of the chamber is effectively broken up. The apertures 71 in being located substantially 90° from the apertures 22 cause the mixed air and fuel vapors to swirl or turn in the mixing chamber 12 in order to pass out through the manifold 25. This rotary motion of the mixture sets up a centrifugal action 75 which brings about a more complete vaporiza-

tion or breaking up of the liquid fuel, and throws the unvaporized fuel outwardly so that it may contact with the heated walls of the mixing chamber 12. In this manner, the liquid fuel is completely broken up or vaporized and completely mixed with the air, producing an efficient highly combustible mixture for the engine. The single valve 64 of the carburetor controls the flow through the apertures 22, the discharge of liquid fuel from the ports 56, and the outward flow through the apertures 71 so that the correct proportioning of liquid fuel and air is maintained at all speeds of the engine. By proportionately varying the flow through the apertures 71 with the varying of the admission of liquid fuel and air into the mixing chamber 12, a flow condition is maintained in the mixing chamber 12 that insures the proper breaking up and mixing of the liquid fuel. The liquid fuel is heated as it passes through the port 49 and recess 53 and is discharged from the ports 56 while hot. It will be apparent how the wings 66 of the valve 64 are operable to successively cover and uncover the fuel inlet ports 56, and at the same time vary the admission of air through the apertures 22 to maintain a proper balance between the liquid fuel and air admitted to the mixing chamber 12. As the carburetor of the present invention effectively pre-heats the liquid fuel and insures the complete vaporizing of the fuel and proper mixing of the fuel with the air, it is adapted to effectively handle comparatively heavy fuel such as kerosene, distillates, etc. The carburetor is operable to produce mixtures of air and comparatively heavy fuels that successfully and efficiently operate internal combustion engines. The carburetor is compact and inexpensive of manufacture, and embodies only a single moving part, namely the valve 64. The valve 64 in being a rotary valve and in having large effective sealing surfaces is long wearing, and does not have a tendency to jam or become inoperative.

Having described only a typical form and application of my invention, I do not desire to restrict or limit myself to the specific form and application set forth, but wish to reserve to myself any variations that may appear to those skilled in the art of fall within the scope of the following claims.

Having described my invention, I claim: 50

1. A carburetor including, a body having an air passage, a partition across the passage having an aperture, a manifold in the body surrounding the upper portion of the passage for circulating heated gases, a member projecting 55 above the partition having liquid fuel ports for discharging into the upper portion of the passage, a body part extending through said manifold and having a fluid passage delivering fuel to the said ports, and a valve for controlling the flow 60 through said aperture and for closing said ports.

2. A carburetor including, a body having an air passage, a partition across the passage having an aperture, a manifold in the body surrounding a portion of the passage for circulating heated gases, a member having spaced liquid fuel ports for discharging outwardly toward the heated wall of said portion of the air passage, the said ports being in the direct line of flow through the said aperture, and a valve for cutting off said aperture and for successively closing 65 said ports.

3. A carburetor including a body having an air passage and an internal structure having a liquid fuel supply passage, an apertured tube 75

projecting inwardly from the outlet end of the air passage, a member having ports discharging liquid fuel from the supply passage laterally outward into the passage at points circumferentially spaced with respect to said aperture of the tube, and a single valve for successively closing the ports and for closing the apertures.

5. A carburetor including, a body having an air passage, a partition across the passage having an aperture, a manifold in the body surrounding the passage for circulating heated gases, a member at the partition having a liquid fuel port discharging laterally against the heated wall of the passage, and a rotatable valve for simultaneously controlling the flow through the aperture and for closing the port.

10. A carburetor including, a body having an air passage, a partition across the passage having an aperture, a manifold in the body surrounding the passage for circulating heated gases, a member at the partition having a liquid fuel port discharging laterally against the heated wall of the passage directly above the partition, and a rotatable valve for simultaneously controlling the flow through the aperture and for closing the port.

15. A carburetor including, a body having an air passage, a partition across the passage having an aperture, there being a recess in the partition, the body having a liquid passage delivering liquid fuel to the recess, a member having liquid fuel ports for discharging laterally into the air passage above the partition, capillary tubes on the member extending into the liquid fuel in the recess and supplying said ports, and a rotatable valve having an aperture movable into and out of register with the ports and said aperture.

20. A carburetor including, a body having an air passage, a partition across the passage having an aperture, there being a recess in the partition, the body having a liquid passage delivering liquid fuel to the recess, a member having liquid fuel ports for discharging laterally into the air passage above the partition, capillary tubes on the member extending into the liquid fuel in the recess and supplying said ports, and a rotatable valve having an aperture movable into and out of register with the ports and said aperture.

25. A carburetor including, a body having an air passage, a partition across the passage having an aperture, there being a recess in the partition,

the body having a liquid passage delivering liquid fuel to the recess, a member having liquid fuel ports for discharging into the air passage above the partition, capillary tubes on the member extending into the liquid fuel in the recess and supplying said ports, a manifold surrounding the portion of the air passage above the partition and the liquid passage, and a valve controlling the ports and said aperture.

30. A carburetor including, a body having an air passage, a partition across the passage having an aperture, there being a recess in the partition, the body having a liquid passage delivering liquid fuel to the recess, a member having liquid fuel ports for discharging into the air passage above the partition, capillary tubes on the member extending into the liquid fuel in the recess and supplying said ports, a tube extending downward from the outlet end of the air passage, the tube having apertures spaced circumferentially from the aperture in the partition, and a valve for simultaneously controlling the aperture in the partition, the fuel ports and the apertures in the tube.

35. A carburetor including, a body having a fluid passage, a member in the passage having a fuel port discharging into the passage, means for supplying fuel to the port, an assembly of two telescopically arranged members in the body having a closed lower end and an open upper end communicating with the outlet of the passage, one member being rotatable relative to the other, a part of the rotatable member cooperating with the fuel port, there being openings in the said two members adapted to register to allow a flow through the passage, and means for rotating the said rotatable member to simultaneously close the fuel port and control the flow through the passage.

OREN F. TEED. 40
